UNITED STATES PATENT OFFICE.

BAPTISTE YCRE, OF NEW YORK, N. Y.

BAKER'S OVEN.

SPECIFICATION forming part of Letters Patent No. 790,862, dated May 23, 1905.

Application filed June 1, 1904. Serial No. 210,710.

To all whom it may concern:

Be it known that I, BAPTISTE YCRE, a citizen of the United States, residing in New York, borough of Manhattan, in the State of New York, have invented certain new and useful improvements in Bakers' Ovens, of which the following is a specification.

This invention relates to certain improvements in bakers' ovens by which the output of the oven and the capacity of the same are increased to such an extent that one oven has a capacity of from five to six ordinary ovens without increasing the floor-space required for one ordinary oven and which has the advantage that two or more men can work at the oven for charging and discharging the articles to and from the baking-chamber; and the invention consists of a bakers' oven that is divided by means of an interior gate into two chambers—a charging-chamber and a baking-chamber—the charging-chamber being provided with transverse track-rails and with a truck which is movable on said track-rails and provided with longitudinally-grooved ways that are placed in line with wheeled baking-racks arranged in rows in the baking-chamber.

The invention consists, further, in the improved construction of the interior gate and its closing-blocks, the means for shifting the closing-blocks, and in the means for lowering or raising the entire interior gate for giving access to the baking-chamber, and the invention consists, lastly, in the constructive details of the baking racks and shelves, which will be fully described hereinafter, and finally pointed out in the claims.

In the accompanying drawings, Figure 1 represents a front elevation of my improved bakers' oven, showing the main gate raised and the auxiliary front and interior gates in closed position. Fig. 2 is a front elevation showing the main gate raised, the auxiliary front gate closed, and the interior gate in lowered or open position. Fig. 3 is a vertical transverse section through the main and auxiliary front gates drawn on a larger scale. Fig. 4 is a vertical longitudinal section through the charging and baking chambers, showing the front gate and the interior gate in closed position. Fig. 5 is a horizontal section on

line 5 5, Fig. 1, through the charging and baking chambers. Fig. 6 is a vertical transverse section through the charging-chamber and interior gate drawn on a larger scale; and Figs. 7 and 8 are respectively a perspective view of the truck by which the baking-racks are transferred from one side of the baking-chamber to the other and a vertical transverse section of the truck on line 8 8, Fig. 7.

Similar letters of reference indicate corresponding parts.

The oven is divided by an interior transverse gate G, that is located at some distance from the front wall A of the oven, into a larger compartment or baking-chamber C 65 and a smaller compartment or charging-chamber B, which is located between the front wall A and the interior gate G. The baking-chamber is made of fire-brick and arched in the usual manner, but of greater height than 70 the baking-chamber of an ordinary baker's oven, so as to provide for the introduction of a plurality of baking-racks R, which are made of sufficient height so as to support a plurality—say five or more—of superposed baking-shelves. The charging-chamber B is made of corresponding height, so as to provide for the height of the baking-racks, while the opening o in the front wall and the opening o' in the wall between the charging and baking chambers are also made of sufficient size to permit the introduction of the baking-racks into the charging-chamber and from the same into the baking-chamber and the removing of the same from one chamber to the other. In front 85 of the opening o in the front wall A is arranged a horizontal charging board or shelf A', on which the articles to be baked are placed, so as to permit the ready transference of the same to the baking-racks in the charging-chamber after the front gates are opened and then into the baking-chamber after the interior gate G is opened. The charging and baking chambers are heated up by means of flues which are arranged in the side, rear, and 90 top walls of the oven and through which the products of combustion from the fireplaces F are conducted to the chimney, so as to permit the preparatory and permanent firing of the baking-chamber. The products of combustion 95 100

tion are first drawn through the side flues to the rear flues, then in upward direction to the top flues, then in forward direction through the top flues to the chimney, the flue connections being made in any approved manner, so that a thorough distribution of the products of combustion in the flues and the uniform heating of the walls of the charging and baking chambers is obtained.

- 10 *The front gates.*—The opening o in the front wall of the oven extends for the full width of the oven and is surrounded by an iron frame E of rectangular shape, which is closed by a main gate E' , that is suspended from a suitable chain e' , passing over pulleys e^2 and counterbalanced by a weight e^3 , so that the main gate can be readily opened or closed. The main gate E' is guided in vertical ways of the frame E , as shown in Figs. 1, 3, and 5. Adjacent to and back of the main gate E' is arranged a second or auxiliary front gate E^2 , which is likewise suspended from a chain e^4 , that is guided over pulleys e^5 and counterbalanced by a weight e^6 , so as to be readily raised or lowered. The auxiliary front gate E^2 consists of a rectangular frame E^3 , which is provided in its bottom with grooved ways e^6 and near its ends with vertical guideways e^7 . The vertical guideways e^7 serve for guiding smaller gates e^8 , one at each end, which are counterbalanced by weighted chains e^9 , that are applied to the upper hook-shaped ends of rods e^9 , attached to the end gates, said counterbalancing-chains e^9 being guided over pulleys e^{10} on the front wall of the oven, so that the end gates can be separately raised or lowered independently of the main gate E' for giving access to the right and left hand sides of the charging and baking chambers. Between the end gates E^4 and in alinement therewith is arranged a plurality of closing-blocks E^5 , which are guided in the bottom ways e^6 of the frame E^3 and shiftable therein, four of these blocks being shown in the drawings.
- 45 The end gates E and shiftable closing-blocks E^5 are made of wrought-iron or other suitable material and are connected at their adjacent sides by tongue-and-groove joints, so as to produce the tight closing of the charging-chamber. The closing-blocks E^5 are provided with rack-teeth at their lower ends and made to intermesh with intermediate pinions e^{11} , the shafts of which are supported in bearings in the lower part of the main frame E , said pinions being again placed in mesh with gear-wheels e^{12} , which are keyed to tubular shafts s , that are provided at their front ends with hand-wheels s' . The gear-wheels e^{12} and their tubular shafts s are supported in a casing arranged below the frame E of the front gates E' E^2 of the oven, as shown in Figs. 2 and 3. The tubular shafts s and the gear-wheels e^{12} and pinions e^{11} , interposed between the shafts and the closing-blocks E^5 , serve for the purpose of shifting the blocks E^5 either toward

the right or left in the frame E^3 after the end gates E^4 are placed in raised position, so as to give thereby access to any portion of the charging and baking chambers. The main gate E' and the auxiliary front gate E^2 , composed of the frame E^3 , end gates E^4 , and shiftable closing-blocks E^5 , are raised whenever the entire front opening o of the oven is to be opened, so as to give access to the entire width of the charging and baking chambers when this is desired for inserting or removing the baking-racks, cleaning the sole of the baking-chamber, and for other purposes. During the ordinary use of the oven the main gate E' and the auxiliary front gate E^2 are in their lowered position, as shown in Figs. 1 and 4, and access is given to the charging and baking chambers by first raising the main gate E' , then one of the end gates, and then shifting one of the closing-blocks toward the right or left into the space before occupied by the end gate, so that as little heat as possible is permitted to escape from the charging-chamber during the charging and discharging of the oven. The space for shifting the closing-blocks E^5 to the left or right is obtained by raising either one or both of the end gates E^4 to the fullest extent. By this arrangement access may be given to any part of the charging and baking chambers either at the sides of the same by simply raising one or both end gates E^4 or at any intermediate part of the same by raising the end gates and then shifting the closing-blocks to one side or the other.

The large opening in the front wall of the oven, together with the main gate and the auxiliary front gate with its end gates and shiftable closing-blocks, can be used in connection with any ordinary baker's oven, the improved front gates having the advantage that two men can work at the oven instead of one for charging the articles to be baked and discharging the baked articles, while heretofore only one man could work at the narrow charging-opening of an oven at one time.

The charging-chamber.—The interior gate G is arranged at such a distance from the front gates E' E^2 that a charging-chamber of sufficient size is obtained in which the baking-racks R can be readily moved transversely from one side to the other for the convenient transference of the racks from the charging-chamber to the baking-chamber, and vice versa, from the baking-chamber to the charging-chamber, as required. The level of the bottom of the charging-chamber B is somewhat below the level of the top surface of the front board or shelf A' and below the level of the sole of the baking-chamber, so as to permit the arrangement of transverse track-rails d on the bottom of the charging-chamber, on which is guided a wheeled truck D , which is shown clearly in Figs. 6 and 7. The truck D is made of oblong shape, its length being equal with the width of the charging-chamber B

and provided on its top surface with longitudinally-grooved ways d' , that extend from the front to the rear end of the truck, so as to permit the wheels of the baking-racks to be run into the grooved ways d' of the truck and the moving of the truck with the baking-rack on the same from one end of the charging-chamber to the other. The truck D is provided at its under side with a transverse rack d^2 , which is preferably located at the middle portion of the truck and engaged by pinions d^3 , that project through slotted openings d^4 in the bottom of the charging-chamber B, said pinions meshing with gear-wheels d^5 , that are keyed to tubular shafts s^2 , located in the tubular shafts s of the operating-gears of the closing-blocks E⁶. The tubular shafts s^2 are provided with hand-wheels s^3 in front of the hand-wheels s^4 and supported at the rear ends in bearings of a transverse casing d^6 below the bottom of the charging-chamber, as shown in Fig. 4. By turning the tubular shafts s^2 in one or the opposite direction the truck D is moved by the pinions d^3 gradually through the charging-chamber to one side or the other, as required. Adjacent to and in front of the pinions d^3 the bottom of the charging-chamber B is provided with oblong sockets d^7 for inserting stop-pins d^8 , by which the truck can be locked in position, as shown in Fig. 5, axially in line with the baking-racks in the baking-chamber for permitting the transfer of the racks from the baking-chamber to the truck in the charging-chamber, and vice versa, the return of the baking-racks from the charging-chamber into the baking-chamber. When the truck with the baking-rack on the same is held in position by the stop-pins d^8 , they are also axially in line with a corresponding open space formed in the auxiliary front gate E² either by the raising of the end gates or the shifting of the closing-blocks E⁶, so as to permit the convenient charging or discharging of the shelves of the baking-rack through the open spaces in the auxiliary front gate.

The interior gate.—The interior gate G is guided in vertical ways of a rectangular main frame G¹, which is open at its lower part. The gate G is composed of an oblong guide-frame G², two laterally-shiftable end blocks G³, and intermediate shiftable closing-blocks G⁴, as shown in Fig. 5. The end blocks G³ and closing-blocks G⁴ are guided in parallel ways g in the bottom of the guide-frame G², the end blocks G³ being guided in the front ways and the intermediate blocks in the rear way g . Both the end blocks and intermediate blocks are made shiftable to one side or the other, like the closing-blocks of the auxiliary front gate, by pinions g' , which project through openings in the bottom of the guide-frame G² and mesh with the toothed lower ends of the end and intermediate blocks G³ G⁴, the pinions g' being supported in bearings of the guide-frame G² and operated by two sets

of intermeshing gear-wheels g^2 . The front gear-wheels g^2 are provided with tubular shafts g^3 and the rear gear-wheels g^2 with solid shafts g^4 , which extend through the tubular shafts g^3 . The shafts g^3 are engaged in any suitable manner by the socket-shaped rear ends of tubular shafts s^4 , so as to be turned in one or the opposite direction by the same, said shafts extending through the tubular shafts s^2 and being provided in front of the hand-wheels s^3 of the latter with actuating hand-wheels s^5 , while the shafts g^4 of the rear gear-wheels g^2 are adapted to be coupled by the rear ends of shafts s^6 , that are extended through the tubular shafts s^4 and provided at their front ends with hand-wheels s^7 . The end blocks G³ and intermediate blocks G⁴ are shifted by the action of the shafts s^3 s^6 and the intermediate transmitting gears and pinions in the bottom ways of the guide-frame G², so as to provide the space required for moving the baking-racks from the baking-chamber into the charging-chamber and back into the baking-chamber and give thereby, in connection with the end gates and shiftable blocks of the auxiliary front gate, access to any part of the baking-chamber. The guide-frame G² of the interior gate G is extended to a sufficient distance below its bottom, so as to provide the necessary space for the motion-transmitting pinions and gear-wheels, and is swiveled at its lower end to a screw-spindle G⁵, having a hand-wheel G⁶ at its lower end, the screw-spindle engaging a central screw-nut g^7 of the stationary yoke G⁷, arranged in a recess B' below the charging-chamber B, so as to give access to the screw-spindle and produce by the turning of the same by its hand-wheel the raising or lowering of the entire gate-frame G², with its end and intermediate blocks, so that access is given for the entire width of the baking-chamber for placing the baking-racks in position therein or for the removing of the racks and cleaning the sole of the baking-chamber. The recess B' below the charging-chamber B is preferably closed at its front end by a suitable panel p, which is removed whenever the interior gate is desired to be raised or lowered in its entirety.

Operation.—For starting the oven it is necessary to introduce first the full complement of baking-racks into the baking-chamber. This is accomplished by opening entirely the front gates by raising them to their full extent and the interior gate by lowering it to the full extent. One rack after the other is then placed in position on the truck in the charging-chamber and from the same moved to the rear part of the baking-chamber, the next rack in front of the rearmost rack, and so on until the first row is in position in the baking-chamber. The racks of the next row are then placed in position in the baking-chamber by moving the truck laterally in line

with the axis of the second row. The truck is again moved laterally in the charging-chamber for placing the third row of racks in position, and so on until the entire baking-chamber is filled with racks, a space corresponding to one row of racks being left unoccupied at one side of the baking-chamber, as shown at the left-hand side of Fig. 5. The gates are then closed and the preliminary heating of the oven started. The racks remain in the oven without being removed therefrom. They are then charged with the articles to be baked by opening the corresponding end gates and closing-blocks of the front and interior gates, moving one rack after the other into the charging-chamber, placing the articles thereon, and returning the racks into the baking-chamber. This is accomplished by means of the vacant space at one side of the baking-chamber, which permits the shifting of the racks row by row in the baking-chamber in connection with the truck in the charging-chamber. When the shelves of all the racks are charged, the closing-blocks and the front main gate are closed, the oven permanently fired, so as to bake the articles on the racks. After the baking operation is completed one rack after the other is moved on the truck in the charging-chamber, starting at one side of the baking-chamber, and the baked articles are discharged into a basket by moving the rakes on one shelf after the other in forward direction. The rack is then moved transversely with the truck to the opposite side of the charging-chamber to the farthest rear end of the same. The next rack is then moved onto the truck, the baked articles are removed by the rakes in the same manner as before, the truck is moved over into line with the vacant space in the baking-chamber, and the rack moved backward into a position adjacent to the rack before put in, and so on until the vacant space is filled with racks. The row of racks next adjacent to the space just filled is then moved forward into the charging-chamber one after the other, the articles thereon are removed, and the racks placed in the vacant space formed at the opposite side of the baking-chamber adjacent the first row of racks that has been moved over into the vacant space, so that this side of the oven is charged again with racks. The remaining rows of racks are then moved forward in the same manner into the vacant space formed by the rows of racks just removed until the articles from all the racks are discharged and the same replaced in proper position. When several batches are to be baked by one heat of the oven, all the racks are again charged before being returned into their position in the baking-chamber. After all the racks are replaced in the baking-chamber, the front and interior gates are closed again and the second baking operation takes place. When this is accomplished, the baking-racks are removed

again in the same manner by shifting one rack after the other first into the charging-chamber, removing the baked articles, replacing them with new articles, and then shifting the racks back into their proper position in the baking-chamber. In this manner a very large quantity of articles can be baked in one heat of the oven, and thereby the output of the oven greatly increased.

The improved oven saves considerable floor-space, as it takes the place of four or five ovens heretofore necessary, permits the utilization of the heat of the oven in a superior and more economical manner than heretofore, and permits the operation of transferring the racks into the charging-chamber, of charging and discharging of the racks, and then returning them into the baking-chamber by the joint operation of two men, while heretofore only one man could attend an oven at the same time.

Having thus described my invention, what I claim as my invention, and desire to secure by Letters Patent, is—

1. In a baker's oven, the combination, with a baking-chamber and a charging-chamber in communication therewith, of a separating-gate between said chambers, comprising a frame having a plurality of shiftable blocks or panels guided therein, said frame being movable downwardly below the baking-chamber floor.

2. In a baker's oven, the combination, with the baking-chamber and a charging-chamber in front of the same, of an interior separating-gate between said chambers, said gate being composed of a guide-frame provided with two parallel ways, closing-blocks at each end of one of said ways, closing-blocks between the end closing-blocks, guided in the other way of the guide-frame, and means for shifting the end closing-blocks and intermediate closing-blocks independently of each other in the ways of the guide-frame.

3. In a baker's oven, the combination, with a baking-chamber and a charging-chamber in front of the same, of an interior separating-gate between said chambers, a main gate at the front end of the charging-chamber, a truck in said charging-chamber, and means for moving the truck transversely from one side to the other in the charging-chamber.

4. In a baker's oven, the combination, with a baking-chamber and a charging-chamber in communication therewith, of a separating-gate between said chambers, a plurality of spaced pinions aligned transversely of said charging-chamber, a transversely movable truck arranged in said charging-chamber and provided with a rack for successively engaging said pinions, and means for independently actuating each of the latter.

5. In a baker's oven, the combination, with a baking-chamber and a charging-chamber in front of said baking-chamber, of gates for opening or closing both chambers, transverse

5 rails in the charging-chamber, a truck in said charging-chamber, movable on said rails and provided with longitudinal guide-grooves for the baking-racks, and means for moving the truck from one side to the other in said charging-chamber.

6. In a baker's oven, the combination, with a baking-chamber and a charging-chamber in front of said baking-chamber, of gates for opening or closing each of said chambers, a truck in the charging-chamber, means for moving the truck from one side to the other of the charging-chamber, and means for locking the truck in position in said charging-chamber.

15 7. In a baker's oven, the combination, with a baking-chamber and a charging-chamber in front of the same, of a plurality of baking-racks

adapted to be arranged in rows in the baking-chambers, a truck located in the charging-chamber, and means for moving the truck transversely in the charging-chamber into line with either one of the rows of baking-racks, said truck being provided with longitudinal grooves for receiving one of the racks 20 at a time and transferring it from one place in the baking-chamber to another place in the same.

25 In testimony that I claim the foregoing as my invention I have signed my name in presence of two subscribing witnesses.

30 BAPTISTE YCRE.
